Charles Carr

UNITED STATES PATENT OFFICE.

CHARLES CARR, OF BOSTON, MASSACHUSETTS, ASSIGNOR TO JAMES BENNETT
FORSYTH, OF SAME PLACE.

DESIGN FOR A MAT.

SPECIFICATION forming part of Design No. 20,108, dated August 26, 1890.

Application filed March 31, 1890. Serial No. 346,086. Term of patent 14 years.

To all whom it may concern:

Be it known that I, CHARLES CARR, of the city of Boston, county of Suffolk, and State of Massachusetts, have invented and produced a new and original Design for Mats, &c., of which the following is a full and complete description, reference being had to the accompanying photograph, forming a part of this specification.

- 10 The design comprises a central field ornamented with several series of circles and lines, and a border inclosing this field, which is ornamented with a series of leaves, &c., all substantially as hereinafter more fully described.
- 15 The central field or panel has a configuration consisting first of diagonal lines at an angle of forty-five degrees, with the border in two reverse series and terminating against a ribbon of two lines, with a space between them divided into parallelograms by cross-lines. From the intersections of the diagonal lines as a center are drawn circles whose circumferences have a common intersection and coincidence at the diagonal line. From the alternate intersections of the diagonal lines is drawn a larger circle, the circumferences of which meet and coincide at points central between the intersections of the diagonal lines. Around these centers or alternate intersections of the diagonal lines and at a central

position with respect to the diagonal lines and the smaller circles, and within said smaller circles, is disposed, four to each, still smaller circles. Around the margin these larger and second size circles are cut and terminated by 35 the ribbon margin above described. Around said ribbon margin are disposed in reverse order pairs of leaves, the stems of which separate and surround the individual leaves by passing to either side. Coming together they 40 cross each other between the points of two adjacent leaves and forming a loop on either side in line with the edges of the leaves, and interlacing, as shown, with the loops of a quadrilateral four-looped figure the curves 45 of one pair of stems meet those of the next near their junction. Around this series of ornamentation or border configuration is disposed a second ribbon similar to the first described, the outer edge of which is molded 50 in ogee or other desired form. Four small figures are disposed about the quadrilateral four-looped figure, as shown.

I claim—

The design for a mat, substantially as shown 55 and described.

CHARLES CARR.
